Primary Examiner — Catheri Oliver-Garcia(74) *Attorney, Agent, or Firm* — Andrew F. Young, Esq.;
Lackenbach Siegel, LLP(57) **CLAIM**

The ornamental design for a pill container, as shown and described.

DESCRIPTION

FIG. 1 is a front perspective view of the present invention.
FIG. 2 is a front elevation view of FIG. 1.

FIG. 3 is a right side elevation view of FIG. 1, the left elevation view being a mirror image thereof.

FIG. 4 is a rear elevation view of FIG. 1.

FIG. 5 is a top plan view of FIG. 1; and,

FIG. 6 is a bottom plan view of FIG. 1.

The dashed broken lines in FIGS. 1-6 indicate disclaimed matter and no claim is made thereto. The top and bottom surfaces are not claimed at all and this is shown as boundary lines with disclaimed lines therein, but there is no claim for the entire top or bottom surface.

1 Claim, 1 Drawing Sheet(56)
